UNITED STATES PATENT OFFICE.

THOMAS J. FLAGG, OF NEW YORK, N. Y.

DESIGN FOR A MAN'S SCARF.

SPECIFICATION forming part of Design No. 15,142, dated July 15, 1884.

Application filed May 3, 1884. Term of patent 14 years.

To all whom it may concern:

Be it known that I, THOMAS J. FLAGG, of the city, county, and State of New York, have invented a new and original Design for a Scarf for Men's Wear; and I do hereby declare that the following is a full and exact description thereof, reference being had to the accompanying drawing, and to the letters of reference marked thereon, making a part of this specification.

The principal feature of my design consists in the configuration of the outer apron, S, of the scarf, which, as shown in the drawing, is bounded by the elliptically-curved line C D, terminating about midway of the length of the apron in an outwardly-diverging straight line, D G, from which an inwardly-inclined line, G F, extends to the lowest point of the apron, and there forms an angle approaching more or less closely a right angle with a line, F E, equal in length to the line F G, and which, terminating at the same distance from an imaginary central line, xx , bisecting the angle F, as does said line F G, forms an angle, E, with an inwardly-inclined line, E A, the counterpart of the opposite line, G D, so that the points A and D are equally distant from the imaginary line xx . From the extremity A of the line E A a straight line extends, with an inward inclination toward the upper end of the apron, so as to intersect the imaginary line xx at a point, H, near to said upper end, and a line extending from said point H to the initial point C completes the outline of the apron.

The configuration of the entire scarf is completed by an elliptically-curved line, A B, which, as a counterpart of the line C D, ex-

tends from the angle A to a point, B, opposite the upper extremity, C, of the outline of the apron S, and at an equal distance from the imaginary central line, xx , the two points B and C being joined by the straight or slightly-curved line B C. The point H on the line A H C is joined to the point B by a straight line, H B, which is equal in length with the line H C.

In the design thus produced the lines C D, D G, G F, F E, E A, and A C define the edges and include the surface of the outer apron, S, of the scarf. The lines A B, B H, and H A define the edges and include the exposed surface of its inner apron, T, and the lines B H, H C, and B C define and include the exposed surface of its center piece, U.

I claim—

The design for a made-up scarf, herein shown and described, the same consisting of the irregular outline A H, H C, C D, D G, G F, F E, E A, defining the outer apron of the scarf, in combination with the outline A B, B H, H A, which, coinciding at A H with a portion of the outline of the outer apron, defines the inner apron, and with the line B C, which, uniting the upper extremities of the two lateral curved lines B A and C D, defines the neck-line and completes the configuration of the entire scarf.

In testimony whereof I have signed my name to this specification in the presence of two subscribing witnesses.

THOMAS J. FLAGG.
